UNITED STATES PATENT OFFICE.

JOHN L. KIVLAN, OF BOSTON, MASSACHUSETTE.

JAR-CLOSURE.

Specification of Letters Patent. Patented June 28, 1921.

1,383,215.

Application filed March 7, 1919. Serial No. 281,307.

To all whom it may concern:

Be it known that I, JOHN L. KIVLAN, a citizen of the United States, residing at Boston, in the county of Suffolk and State of Massachusetts, have invented certain new and useful Improvements in Jar-Closures; and I do hereby declare the following to be a full, clear, and exact description of the invention, such as will enable others skilled in the art to which it appertains to make and use the same.

This invention relates to jar closures and particularly to an improvement in the type of jar closure disclosed in the patent issued February 23, 1909, No. 913214.

One of the objects of the present invention is to reduce the number of individual elements going to comprise the organization and therefore to reduce the cost of assemblage of the parts and at the same time to reduce the cost of construction. Another object of the invention is to provide parts which are readily assembled and yet which are substantial, durable, and also accomplish the effectual clamping of a cover on to a sealing gasket to secure the effectual closure of the container on which the cover may be arranged.

With these and other objects in view as will be rendered manifest in the following specification to those skilled in the art the invention consists in the construction, combination, and in details and elements of the parts as more particularly set forth in the following specification with relation to the embodiments of the invention illustrated in the accompanying drawings herein:

Figure 1 is a vertical, central section through the upper portion of a fragment of a jar with the closure applied and clamped.

Fig. 2 is a side elevation of the upper portion of the jar with the clamping means disengaged to release the cover.

Fig. 3 is a side elevation of the closure in the clamping position viewed from a point at right angles to the plane in Fig. 2.

Fig. 4 is a side elevation of a fragment of a jar showing a modified form of pivot ring support.

Fig. 5 is an enlarged detail of the toggle link, showing its angular abutment face.

Fig. 6 is side elevation of a modified form of clamping member in position.

Fig. 7 is a side elevation of the modified clamp viewed from a point at right angles to the plane in Fig. 6.

Fig. 8 is a cross section of a jar showing a modified toggle pivot, and,

Fig. 9 is a side elevation of the pivot shown in Fig. 8.

I have illustrated my improved clamp as applied to a convenient form of jar J, on a circumferential rim or shoulder on which is provided a gasket R to receive the flange of the cover or top T this latter being clearly shown in Fig. 1 as being provided with a circular groove on its top face at g for a purpose hereinafter specified. The outer surface of the neck of the jar is provided with an annular shoulder C just below which there is disposed a wire or ring W preferably of such diameter as not to project above the shoulder C. Directly and pivotally mounted on this wire ring is a toggle link or member L shown as comprising a piece of bent tin plate or suitable material of suitable width having an over-turned upper ear or hub forming a hinge portion to swing on the included wire, the hub portion h being flattened tangentially at i to abut against the adjacent surface C so that an effective seating or abutment between the toggle link L and the seat is secured. The lower or swinging end of the toggle link L is shown as rolled over to pivotally receive the transverse bar of a wire or other link or hook member D which is slightly outwardly curved when observed edgewise so as to freely pass over the protruding neck portion of the bottle when the hook, of which it might be stated, there is one on each side of the bottle, is arranged in the clamping position Fig. 1 at which time the upper portion or nib d of the hook is drawn downwardly into the groove g of the cover or top T. This drawing down or clamping action of the hook or hooks D occurs after the cover T has been put in place and the hook D swung downwardly from the position shown in Fig. 2 to the position shown in Fig. 1 whereupon inasmuch as the toggle link L swings beneath its pivot on the ring W the hook D is placed under tension as its nib d brings up against the top T and its lower end, which is connected with the swinging link L, passes toward the jar.

As clearly shown in Fig. 4 in which the hook is shown as swung outwardly from the surface of the jar, the nib of the hook is formed of a transverse bar which is curved to conform to the curvature of the circular groove g in the top of the jar closure so that

the hook seats snugly in position against the curved surface of the groove shown in a circumferential direction and also in a vertical direction where the hook enters downwardly into the groove. By this structure the toggles are retained in an operative position irrespective of the amount of pressure which they exert. It will be further noted that the portion of the jar cover within the circular groove g is on a higher plane than the circumferential ridge on the outer side of the groove g . By reason of this structure, in applying the fastening members the nibs are permitted to pass over the external ridge and then engage the higher central part of the top, whereupon by pressure being applied to the members D the top can be readily centered on the jar without being touched.

From the above it will be seen that I have provided an extremely simple means of clamping the jar closure in position and that the closure comprises a simple and inexpensive ring having pivoted at diametrically opposite points a pair of toggle links L swinging directly on the wire ring and carrying at their outer ends the wire hooks or tension members D which are designed to snugly engage the grooved portion of the cover so as to prevent accidental removal of the parts after the same have been set in clamped position and so that the hook can only be removed by first swinging outwardly its bottom end which is connected with the toggle link L .

To prevent downward movement of the ring on which the toggle links L are mounted suitable means may be employed or formed upon the jar body as for instance in Fig. 3 the jar neck may be provided with a circular shoulder or projection P spaced sufficiently below the shoulder C to form a channel or groove for a reception of the wire ring W . A slightly modified form of the ring retaining device is shown in Fig. 4 in which the support is illustrated as comprising a series of small spurs S in substitution of the head or ring shown at P in Fig. 3.

In Figs. 6 and 7 a slightly modified form of the invention is shown and in which the hook member D' is directly pivoted on the

ring W and has its upper end bent inwardly. Pivoted in this upper end is a staple-shaped nib N the ends of which are designed to enter the groove in the top T . The tension of the member holds the clamp closed.

What I desire to claim is:

1. A jar closure comprising in combination a cover having a peripheral ridge defined by an interior circular groove, and a plurality of clamping members having downturned nibs conformed to the shape of and adapted to seat in said groove within said ridge.

2. A jar closure comprising in combination, a cover having a peripheral ridge defined by an interior circular groove, diametrically opposed toggle joint levers having down turned nibs on one member to engage said groove within said ridge and an annular wire pivoting and frictionally securing said toggles to the neck of the jar.

3. A jar closure comprising in combination a cover, toggles having each a locking shoulder and locking means on the neck of the jar adapted to engage said shoulders on the toggles to secure the latter in a predetermined position.

4. The combination of a jar having a circular ridge on its neck, a cover having a peripheral ridge determined by an interior circular groove, and toggle members adapted to engage both the ridge on the jar and that on the cover.

5. A jar closure comprising, in combination, a cover having a marginal ridge and a plurality of clamping members having downturned nibs adapted to seat on said top within said ridge.

6. As an article of manufacture, a jar cover having on its bottom face an annular seating surface adapted to rest on a gasket on a suitable annular seat on a jar neck, and having on its upper face a peripheral ridge determined by an interior circular groove, the bottom of said circular groove being directly over said annular seat and adapted to receive fastening members, whereby pressure exerted on the bottom of said groove will be transmitted directly to said seat.

In testimony whereof I affix my signature,
JOHN L. KIVLAN.
